SPRING COILING MACHINE

Carl H. Peterson, Worcester, Mass., assignor to
 The American Steel and Wire Company of New
 Jersey, a corporation of New Jersey

Application November 5, 1942, Serial No. 464,631

9 Claims. (Cl. 153—65)

The present invention relates to improvements in spring coiling machines which make it possible to coil noncircular springs of helix-like formation comprised of straight portions connected by curved or arcuate portions. The characteristic features of the present improvement will be fully apparent from the following detailed disclosure when read in connection with the accompanying drawings and will be defined with particularity in the appended claims.

In the drawings, Figure 1 is a plan view of a machine embodying the present invention;

Figure 2 is a sectional elevation taken on the plane indicated by line II—II of Figure 1;

Figure 3 is a similar sectional elevation taken at line III—III of Figure 1;

Figure 4 is a detail section taken on line IV—IV of Figure 2;

Figure 5 is an enlarged horizontal section illustrative of details of the coiling, bending and skewing instrumentalities;

Figure 6 is a detail section on line VI—VI of Figure 5;

Figures 7 and 8 are fragmentary detail sections on the correspondingly numbered lines of Figure 5;

Figure 9 is an enlarged detail fragmentary view illustrative of the mechanism for producing coiled helix-like springs having straight portions connected by bent or rounded portions;

Figure 10 is an enlarged side elevation of one form of noncircular spring adapted to be coiled by the improved machine;

Figure 11 is an end view of Figure 12;

Figure 12 is an end view of a modified form of noncircular spring which the improved machine may be adapted to produce by making suitable adjustments therein;

Figure 13 is a detail partly in elevation and partly in section of an automatically actuated clutch well suited for imparting the intermittent feeding movement to the wire spring stock; and

Figure 14 is a section on line XIV—XIV of Figure 13.

The present invention is directed to rather specific features of design and arrangement of coacting instrumentalities adapted to advance predetermined increments of wire stock and to bend portions of each advanced increment while leaving other portions straight, whereby there is formed a helix-like noncircular coiled spring in which straight unworked portions are connected by bent or curved cold-worked portions. The mechanism, as will hereinafter more fully appear, is so designed and arranged that by

making certain adjustments, various sizes of springs can be made, also the contour of the springs produced can be varied. More specifically, the novel machine of the invention herein

5 claimed comprises a fixed arbor and a fixed skew member combined with means for feeding spring wire stock into coaction therewith and in a position to be acted upon jointly by said parts and by a bending die which is mounted for movement relative to the arbor and having means provided for sequentially moving the bending die and holding it stationary for predetermined intervals while the stock feeding means are advancing the wire so that a non-circular spring is coiled about the fixed arbor in such fashion that each convolution of the spring includes a plurality of bent or curved cold-worked portions which are connected by straight unworked portions.

10 Referring more specifically to the drawings, 10 represents the base portion of the machine which supports substantially parallel frame elements 12, 14, and 16. Power is supplied from a drive shaft 18 journaled in suitable bearings carried by the frame 16. Shaft 18 carries a sprocket 20 around which is trained a chain 22 which in turn drives a sprocket wheel 24 secured to a main shaft 26. Rotating with the shaft 26, there is a manually controlled clutch member 28 adapted to be actuated by a clutch lever 30 pivotally mounted at 32 to a suitable fixed bracket. A coacting clutch member 34 is mounted on the sleeve 36 which is mounted free on the shaft 26. This sleeve carries a drive pinion 38 which meshes with a gear 40 secured to a shaft 42. This shaft 42 carries an automatically controlled clutch indicated as a whole at 44, which clutch is adapted to control the intermittent advance of the wire stock in a manner more fully explained hereinafter. While not limited thereto the clutch 44 is preferably of the construction shown in my Patent 2,286,760, dated June 16, 1942.

15 The gear 40 meshes with a gear 46 which is loosely mounted on a shaft 48. Loosely mounted on the shaft 48 and rotated with the gear 46 there is another gear 50 which drives a gear 52 secured to a shaft 56 journaled in suitable bearings carried by the frames 14 and 16. The gear 52 meshes with a driving gear 58 secured to a shaft 60 journaled in suitable bearings, mounted in the frames 12, 14 and 16. This shaft carries a cam 62 whose active face coacts with a cam follower 64 secured to a lever 66 which is pivoted at 68 to a bracket 70 secured to a rod 72 mounted

between the frames 12 and 14. The lever 66 has a forked end 74 for engagement with a lug 76 carried by a clutch-operating ring 78 which is free in a groove formed in a collar 80 secured to the shaft 42. This collar 80 carries a stud 82 for operating a pivoted dog 84 which has a tooth for coaction with a projection 86 of a clutch element 88. The clutch element 88 is effective to move clutch rollers 90 into and out of driving engagement with clutch members 92 and 94, the member 92 having curved wedge faces 96 which when moved in one direction will effect a driving connection with the shaft 42 and when moved in the opposite direction will permit the clutch member 94 to remain stationary while the shaft 42 continues to revolve. The clutch member 94 includes a hub extension 98 which is loosely mounted on a sleeve 100 surrounding the shaft 42. The hub extension 98 has keyed or otherwise secured thereto a pinion 102 for transmitting movement to a gear 104 at intermittent time intervals when a driving connection is established between the member 92 and the member 94. This intermittent motion under control of the automatically operable clutch 44 is transmitted from gear 104 to the shaft 48 to which the gear 104 is keyed or otherwise secured. This shaft 48 also carries a gear 106 which meshes with a gear 108 carried by shaft 110. The shafts 48 and 110 respectively carry near their outer ends lower and upper pinch or feed rolls 112 and 114. The upper feed roll is mounted in a vertically movable bearing 116 which is pressed downwardly by an adjusting screw 118, the lower end of which reacts against a spring 120 interposed between the end of the adjusting screw and the upper face of the bearing.

A spring wire guide 122 is provided for guiding the spring wire stock into the bite of the feed rolls, this guide having a conventional guide passageway extending therethrough. On the exit side of the feed rolls there is a similar guide 124 which, in the embodiment of the invention illustrated, directs the oncoming wire stock over the top of a fixed arbor 126. The wire is directed over the top of the arbor when right-hand springs, such as herein illustrated, are to be coiled. However, in some cases by making suitable adjustments the wire may be directed to the underside of the arbor so as to coil left-hand springs.

A particular feature of the present invention relates to the novel arrangement of coacting instrumentalities whereby during one portion of the feeding movement or advance of the stock the same will be bent while passing over the mandrel, while for another interval of time the wire will be advancing in a straight condition. Thus, there will be produced a spring of the character illustrated in Figures 10 and 11. In these figures it will be noted that the noncircular coil spring produced is of helix-like form, but it is not a true helix since each convolution consists of a pair of parallel side portions indicated at *a* and *b* which are connected by curved or substantially semicircular portions *c* and *d*. A spring as thus produced will include a multiplicity of curved portions which are cold worked, and a multiplicity of straight portions which, not having been subjected to a bending operation, will not be cold worked. This permits of the formation of a spring with a certain overall warpage or torsional twist therein which is desirable in order that a subsequent tempering or heat treating operation may be employed to bring the straight portions *a* and *b* of all convolutions of a given spring into true parallelism and to bring also the curved or arcu-

ate portions *c* and *d* into alignment or coplanar relation. The curved portions *c* and *d* of each convolution will form as a result of the combined action of the forward feed or advance of the wire stock coupled with the bending action of a die 128 which is moved downwardly as the wire stock advances and thus bend a portion of each convolution downwardly against the restraining action of the arbor 126. At the termination of each bending operation the wire stock is given a slight bend or flexure as indicated at *e* in Figure 10 by the action of a cam-like member 130 herein referred to as a skew member. This skew member coacts jointly with the bending die and the arbor in such a way that as each coil or convolution is formed the requisite amount of lengthwise flexure is effected to produce the approximately helical formation illustrated.

The bending die 128 is adjustably held by means of a clamp 132 in a grooved seat 134 formed in a die holder 136 which is pivotally mounted on a stud 138 secured to the frame 12. The die holder 136 is connected by means of an adjustable link 140 with one arm 142 of a lever which is pivoted at 144 to the frame 12. At its opposite end this lever has an arm 146 formed with a nose portion 148 which is adapted to coact with a cam member indicated as a whole at 150. This cam member is formed of two disks 152 and 154, each having a plurality of tooth-like extensions 156 thereon as illustrated in Figures 5 and 9. The disks which jointly constitute the cam member are adapted to be shifted one relatively to the other and clamped by means of a bolt 158 secured to one of the disks which passes through a slot 160 formed in the other disk. By shifting one of the disks relatively to the other and then clamping them in the desired position of adjustment a variety of contours of noncircular springs can be secured by use of a given machine. This desirable result can be secured by reason of the fact that so long as the nose portion 148 rides on the concentric dwell portion 162 of the cam member the bending die 128 will remain stationary. At different intervals of time, therefore, the feed wheels will be advancing the spring stock and thus the straight portions *a* and *b* of the spring will be formed. As the cam member continues to rotate the inclined face 164 of the tooth 156 will rock the arm 142. This will transmit motion to the die holder 136. Thus the bending die 128 will be moved downwardly, thereby forming the arcuate curved portion of a given convolution. During the formation of the curved portion of the spring the inclined portion 164 of the active one of the disks of the cam member will engage nose 148. For a short time interval this nose will ride on the outer concentric portions 166 of the two disks forming the cam member. As the curved part of the convolution of the spring is completed the face 168 of one of the cam members will turn in a position so as to permit the nose 148 on the end of the arm 146 to move quickly downwardly under the action of a tension spring 170, one end of which is connected to the end of the clamp 132 and the other end of which is secured to a fixed anchorage 172, whereupon the nose 148 will ride on the next dwell portion of the cam members, thus producing another straight portion of a convolution. As the cam rotates the next tooth will come into play and form the next curved crest of a convolution. The spring being formed rotates bodily during the operations described and the skew member 130 comes into play to impart the desired helical flexure at the proper

location, for example as suggested at *e* in Figure 10. Since there are a multiplicity of toothed portions on the cam member 150 and a corresponding number of intermediate dwell portions it will be understood that for one complete revolution or cycle of the cam member a corresponding number of straight and curved portions of each convolution will be produced.

Means are provided for severing the spring stock after a predetermined number of convolutions have been formed. During the severing operation the clutch 44 is disengaged and the coiling operation is momentarily suspended. In short, the wire stock is advanced intermittently for predetermined intervals to produce a spring of desired length and number of convolutions, whereupon the feed is interrupted while the cutting mechanism is brought into play.

The cutting is effected by a vertically movable knife blade 174 adjustably secured to a holder 176 carried by a slide 178 mounted in a gib or guide 180. The slide at its lower end has a laterally extending arm which carries a roller 182 for coaction with a cam 184 secured to the same shaft 69 which carries the clutch-operating cam 62. Knife blade 174 coacts with a fixed blade 186 adjustably secured to a holder 188 mounted on the side frame 12.

During the coiling or forming of noncircular spring described, prior to the severing thereof the outer end of the rotating coil is supported by a trough-like member 192 having a bracket arm 194 which is secured at 196 to the side frame 12. After the spring is severed it slides down the trough 192 by gravity onto a chute leading to a belt conveyor not shown.

In the foregoing for the purpose of simplicity of illustration and disclosure the operation has been set forth with respect to the formation of a spring having parallel straight portions connected by curved or arcuate or semicircular end portions as shown in Figures 12 and 13. By adjusting the coacting parts of the cam 150 it is apparent that the size of the component straight and curved parts of such a spring may be varied. It is also to be understood that by changes in gearing and modifications in the cam 150 springs of other forms can be readily made. For example, a substantially triangular spring as shown in Figure 12 can be produced, this spring having convolutions in the nature of three straight portions connected by three curved portions.

Although in the foregoing detailed disclosure I have described with great particularity the design and arrangement of coacting parts which an actual reduction to practice on a commercial scale has shown to be extremely efficient and highly desirable, it is not to be construed that I am limited thereto since various changes may be made without departure from the spirit and scope of the invention as defined in the appended claims.

I claim:

1. A machine for making noncircular springs comprising a fixed arbor, a skew member adjacent thereto, means for feeding spring wire stock into coaction with the arbor and skew member, a bending die mounted in juxtaposition to said arbor and skew member for movement relative thereto, and means for sequentially moving said bending die and holding it stationary for predetermined intervals while said feeding means are advancing the wire stock into coaction with the arbor, skew member and bending die, whereby a noncircular spring is coiled about the arbor in

such manner that each convolution includes a plurality of bent cold-worked portions connected by straight unworked portions.

5 2. A machine for making noncircular springs comprising a fixed cylindrical arbor, a fixed skew member adjacent thereto, a die holder pivotally mounted adjacent the arbor, a bending die secured to the holder, means for advancing spring wire stock transversely across the arbor and into coaction with it, the bending die, and said skew member, and means for sequentially moving said holder and holding it stationary, whereby the combined action of said die and said arbor and skew member on the advancing wire produces a noncircular coiled spring with convolutions consisting of oppositely disposed curved cold-worked portions connected by straight unworked portions.

10 3. A machine for making noncircular springs comprising a fixed arbor, skew member adjacent thereto, a movably mounted holder carrying a bending die positioned for coaction with said arbor and skew member, means for advancing spring wire stock into coaction with said arbor, skew member, and bending die, and means for sequentially moving said holder and holding it stationary, whereby the combined action of said die and said arbor and skew member on the advancing wire produces a noncircular coiled spring with convolutions consisting of oppositely disposed curved cold-worked portions connected by straight unworked portions.

15 4. A machine for making noncircular springs comprising a fixed cylindrical arbor, a die holder pivotally mounted adjacent the arbor, a bending die adjustably secured to said holder, a fixed skew member mounted adjacent the arbor, means for continuously advancing spring wire stock transversely across the arbor and into coaction with it, the bending die, and said skew member, an operating lever connected to said holder and die-actuating means coacting with said lever having a plurality of respective cam portions and dwell portions for engagement with the operating lever, whereby the combined action of said die and said arbor and skew member on the advancing wire produces a noncircular coiled spring with convolutions consisting of oppositely disposed curved cold-worked portions connected by straight unworked portions.

20 5. A machine for making noncircular springs comprising a fixed cylindrical arbor, a skew member, means for advancing spring wire stock transversely across the arbor and into coaction with it and said skew member, a die holder pivotally mounted adjacent the arbor, a bending die adjustably secured to said holder, an operating lever connected to said holder and means for actuating said die comprising a pair of juxtaposed disk-like plates adjustably secured together and each having a plurality of respective cam portions and dwell portions for engagement with the operating lever, whereby the combined action of said die, said arbor and skew member on the advancing wire produces a noncircular coiled spring with convolutions consisting of oppositely disposed curved cold-worked portions connected by straight unworked portions.

25 6. A machine for making noncircular springs comprising a fixed arbor and skew member, means for feeding spring wire stock into coaction with the arbor and skew member, a bending die mounted for movement relative to the arbor, means for sequentially moving said bending die and holding it stationary for predetermined in-

tervals while said feeding means are advancing the wire stock, a guide supported in juxtaposition to the arbor and bending die for receiving and supporting the free end of the spring as it is being formed, cutting means located between the outer end of said arbor and the inner end of said guide and means for periodically actuating said cutting means after a spring of predetermined length has been accumulated in said guide.

7. A machine for making noncircular springs comprising a fixed arbor and skew member, means for feeding spring wire stock into coaction with the arbor and skew member, a bending die mounted for movement relative to the arbor, means for sequentially moving said bending die and holding it stationary for predetermined intervals while said feeding means are advancing the wire stock, a guide supported in juxtaposition to the arbor and bending die for receiving and supporting the free end of the spring as it is being formed, respective fixed and movable cutter blades located in a zone intermediate the outer end of said mandrel and the inner end of said guide, and means for periodically actuating said movable blade after a spring of predetermined length has been accumulated in said guide.

8. A machine for making noncircular springs comprising a fixed cylindrical arbor, a skew member, means for advancing spring wire stock transversely across the arbor and into coaction

with it and said skew member, a die holder pivotally mounted adjacent the arbor, a bending die adjustably mounted on the holder, an operating member connected to the holder, and a cam made in two parts adjustably secured together effective to actuate the die holder through said operating member, each of said cam parts having a plurality of tooth-like cam portions between which are circular dwell portions and means for rotating said cam intermittently in synchronism with the said wire feed means.

9. In a machine for making noncircular springs intermittently operating wire spring stock feeding means, an arbor and skew member into coaction with which the stock is advanced intermittently by said feeding means, a bending die, means intermittently moved in timed relation with said feeding means effective to move said bending die while the feeding means is advancing a predetermined length of spring stock past said arbor and skew member and to hold said bending die stationary for predetermined intervals while the feed movements continue, whereby a spring is coiled about the arbor comprising several convolutions each having straight portions which were formed while the die was held stationary and curved portions which were formed while the die was being moved relative to said arbor.

CARL H. PETERSON.
